UNITED STATES PATENT OFFICE.

SIGURD L. WALSOE, OF LYNDHURST, AND JOHN P. HILL, OF NORTH PLAINFIELD, NEW JERSEY, ASSIGNEES TO REMINGTON TYPEWRITER COMPANY, OF ILLION, NEW YORK, A CORPORATION OF NEW YORK.

TYPEWRITING MACHINE.

Application filed July 8, 1926. Serial No. 121,134.

Our invention relates to typewriting machines, and more particularly to so-called billing mechanism for such machines.

The present invention is directed to certain improvements on the construction disclosed in the application of Frederick A. Hart filed July 3, 1926, Serial No. 120,403, and, generally stated, is directed to features which contribute to a more rapid, accurate and effective introduction and positioning of the work sheets in a machine of the character disclosed in said application.

The purpose of said machine, generally stated, is to enable various work sheets to be readily and rapidly introduced into the machine and accurately adjusted therein in proper correlation with one or more previously introduced sheets and enable certain of said sheets to be readily introduced rearwardly into the machine from in front of and beneath the platen.

Generally stated, the improvements of the present invention involve the provision of means for automatically lowering the ribbon vibrator when the deflector is moved to effective position; the provision of automatically actuated paper end stops; the provision of means whereby said end stops may be shifted at will independently of the automatic operation thereof; the provision of means whereby the automatically controlled deflector may be readily disconnected from its controlling means and shifted to a position where it will not interfere with a threading of the ribbon in the ribbon vibrator, etc.; and the provision of an improved form of automatically controlled paper deflector and other details of construction, as will be understood from the following specification.

To the above and other ends which will hereinafter appear, our invention consists in the features of construction, arrangements of parts and combinations of devices set forth in the following description and particularly pointed out in the accompanying claims.

In the drawings which illustrate one form of mechanism embodying our invention, and in which various reference characters designate corresponding parts in the different views,

Figure 1 is a fragmentary, vertical, fore and aft sectional view showing a sufficient

number of parts of a typewriting machine 55 to illustrate the present invention in its embodiment therein; the section being taken on the line 1—1 of Figure 2 and looking in the direction of the arrows at said line, and illustrating the parts in normal position. 60

Figure 2 is a fragmentary top plan view of the same.

Figure 3 is a view corresponding in part to Figure 1 but showing the parts in abnormal position. 65

Figure 4 is a fragmentary top plan view showing a modified form of a part of the construction.

Figure 5 is an enlarged, detail, fragmentary, vertical, transverse, sectional view of 70 a part of the mechanism, the section being taken substantially on the line 5—5 of Figure 6 and looking in the direction of the arrows at said line, assuming the parts cut by said line to be substantially in the normal positions. 75

Figure 6 is an enlarged, detail, fragmentary, side elevation of a part of the mechanism as seen from the left of the carriage and with the parts positioned to receive a 80 work sheet I and carbon sheet L'.

Figure 7 is an enlarged, detail, fragmentary sectional view of one of the feed roller carriers and the associated parts; the section being taken on the line 7—7 of Figure 6 85 and looking in the direction of the arrows at said line.

Figure 8 is a diagrammatic, fore and aft, vertical, sectional view illustrating the parts as they appear after the sheets R R' have 90 been introduced in place.

Figure 8^a is a like view showing the parts as they appear ready for adjusting the sheets R R', if necessary, as well as other sheets, with the aid of the line indicator 118. 95

Figure 9 is a like view showing the parts disposed as they appear after the sheet L has been introduced and adjusted in the machine.

Figure 10 is a corresponding view showing the parts disposed as they appear after the sheets I and L' have been introduced and properly adjusted in the machine and the operator is ready to proceed with the writing. 100

Figure 11 is a detail, transverse, sectional view showing the adjustable end stops and some of the associated parts; the section 105

being taken on the line 11—11 of Figure 12 and looking in the direction of the arrows at said line.

Figure 12 is a diagrammatic, fore and 5 aft, vertical sectional view of the parts as they appear when the work sheet L is positioned in the machine with the aid of the auxiliary adjustable end stops 71.

Figure 13 is a detail perspective view of 10 the paper table and the parts carried thereby, shown detached from the machine.

Figure 14 is an enlarged, detailed, vertical, transverse, sectional view of the front paper deflector and the means for mounting 15 the same; the section being taken on the line 14—14 of Figure 2 and looking in the direction of the arrows at said line.

Figure 15 is an enlarged, fragmentary, detail, top plan view, with parts in section, 20 of the feed rollers 143 and the means associated therewith for supporting and applying pressure to said feed rollers; the view in part corresponding to a section taken on the line 15—15 of Figure 1 and looking in the 25 direction of the arrows at said line.

Figure 16 is a detail front elevation of the feed rollers 150 and 151 and the carriers and connecting means therefor, with parts sectioned away.

30 Figure 17 is a like view of the same showing a different adjustment of the feed rollers, and connecting bars of different lengths coacting therewith to accord with the different adjustment of the rollers.

35 Figure 18 is an enlarged, detail, transverse, sectional view of the adjustable end stop 65 and means for supporting and adjusting it; the section being taken on the line 18—18 of Figure 2 and looking in the 40 direction of the arrow at said line.

Figures 19 and 20 are fragmentary, diagrammatic, front views of the line indicator, showing in Figure 19 how it indicates the tops of the printed characters at the 45 printing line without obscuring them, and showing in Figure 20 how the bottoms of the previously printed characters may be made to register with the line indicator when desired.

50 In the present instance we have illustrated our invention embodied in a Remington bookkeeping machine, model No. 23, equipped with the mechanism of the afore- 55 said Hart application and in which the devices of the present invention may be readily incorporated without modifying, or materially modifying, other structural features of said machine as it now exists. It should be understood, however, that the invention 60 is not restricted to use in such machines but may be embodied in typewriting machines generally, whenever found available.

65 The machine embodying the improvements of the present invention may be used in various kinds of billing operations, where

two or more work sheets are to be correlated in the machine and printed at a single operation. However, we do not deem it necessary to describe specifically the many different forms of billing operations in which 70 the machine may be used. It is sufficient for an understanding of the present invention to specifically describe one mode of billing that may be successfully carried out with the aid of the present machine and perhaps briefly refer to some of the various other methods in connection with which the machine may be employed.

One method of using the machine which will be specifically referred to is its employment, for example, by a public service corporation such as, say, an electric light company, for simultaneously, or at one writing, 80 making out a bill, making corresponding entries on the ledger sheet carrying the account, and on a record or register sheet which receives the entries written on all of the individual bill and ledger sheets. In the example referred to, the register sheet and its accompanying carbon sheet remain in 85

the machine. The ledger sheet which usually requires but a single cross line entry at a time, say, for the month for which the entry is made, may be in the nature of a blank 90 with different vertically ruled columns to be filled in under appropriate printed headings; each cross line of the sheet being ruled off horizontally and given over to a different month, and the entire sheet covering 95

a period of anywhere from, say, eighteen to thirty-six months. Means are provided to enable each ledger sheet and its accompanying carbon sheet to be quickly introduced and properly positioned to receive the 100

requisite entries in the line allotted for the month in question without disturbing the previously introduced register sheet. Means 105

also are provided for then quickly entering a bill sheet into the machine in front of the platen, and accurately positioning it in 110

proper correlation with the previously introduced ledger sheet and the printing line. The entries may then be made on the bill sheet and these will be transferred through 115

interposed carbon sheets to the ledger and register sheets. If desired, additional entries may be made on the ledger sheet which are not to appear on the bill or register sheet. The bill and ledger sheets are then 120

rapidly withdrawn from the machine without disturbing the register sheet, and another ledger sheet and a bill sheet may then be quickly introduced as before, and so on.

In some instances the Remington bookkeeping machine model No. 23 is equipped 125 with power driven carriage return mechanism such as is disclosed in the patent to Frederick A. Hart No. 1,567,590, dated Dec. 29, 1925. We have shown the present invention embodied in such a machine, but 130

have shown only so much thereof as is necessary to arrive at an understanding of the present invention in its embodiment therein.

The frame of the machine is of the usual construction and includes a top plate 1 carrying fixed guide rails 2 oppositely grooved to receive crossed anti-friction guide rollers 3. These rollers are also received in oppositely grooved carriage rails 4 at the front 10 and rear of the carriage, said rails being connected with the end bars 5 and 6 of the carriage.

The carriage, which is power driven in the usual manner, is thus supported and mounted to travel from side to side of the machine over the top plate under control of the usual escapement mechanism (not shown), and in some instances under control of the usual tabulator mechanism. This latter mechanism is represented in part in Fig. 1 by the tabulator frame 7, the decimal stops 8 and column stops 9. Said column stops are carried by a column stop bar 10, secured to brackets 11 which project rearwardly from 20 and are fixed to the carriage. In the machine in which the present invention is shown embodied the carriage may be returned by power from a motor 12, as disclosed in said hereinbefore mentioned patent.

In order to prevent work sheets in the machine from extending back from the carriage and fouling on the tabulator frame 7, and the motor 12, etc., there is provided a sheet metal protecting shield or auxiliary paper table 13 which is fixed to the carriage and extends substantially throughout the width thereof. This shield extends substantially horizontally from its forward end where it is fixed to the carriage and projects rearwardly over the tabulator frame 7, the motor 12, etc. The shield 13 is secured by headed screws 14 to a cross bar 15, secured at its ends by screws 16 to upright hexagonal posts 17. The posts are tapped to receive 35 the threaded stems of the screws 16, and also to receive the stems of headed screws 18 that pass through holes in the column stop bar and secure the posts 17 thereto near the ends of said bar.

Any work sheets that may extend rearwardly beyond the carriage, and back beyond the upper edge of the paper table, will rest on the shield and be prevented thereby from fouling on the motor or the tabulator parts.

The platen 19 is carried by the platen frame in the usual manner, said platen frame comprising end plates 20 and 21 united by cross bar 22. The platen frame is connected 60 to the carriage or truck by links 23 in the usual manner, which links ordinarily guide the platen frame in its case shifting movements. The present machine, however, is intended to write only with capital letters 65 or upper case characters and there is, there-

fore, no case shifting movements of the platen and platen frame; the platen frame being firmly held in its upper case position to the carriage. This is readily accomplished by screwing up the usual lower case 70 limiting stops 24, so that they will hold the buffers 25 which surround the platen shaft against the upper case shift stops 26. This holds the platen at all times in its upper case position where it will coat with the outer- 75 most types 27 on the type bars 28. These type bars are mounted in a type bar segment 29 in the usual manner to swing upwardly and rearwardly to printing position where they strike against the front face of the 80 platen. Due to the fact that in the present machine there is no case shifting movement of the platen, the usual case shift keys and means controlled thereby up to the cross bar 22 of the platen frame may be omitted, leaving room for other devices, as will presently appear.

The usual ribbon vibrator mechanism is employed so as to interpose the ribbon in the path of the types 27 at each actuation of 90 a type bar. Only so much of this mechanism is disclosed as is necessary to arrive at an understanding of how it is controlled in accordance with the present invention.

The ribbon vibrator 30 is guided for up 95 and down movement on the type guide 31 in the usual manner. The vibrator is operatively connected at its lower end to an actuating arm 32, by which upward motion is given the vibrator at each printing operation; the arm at this time turning on a pivot 33, and being limited in such movement by a stop 34. The frame, carrier, or support 35 by which the arm 32 is carried, is supported on links 36 that ordinarily enable the frame 100 35 and the parts carried thereby to shift up and down with the platen in its case shifting movements. This ordinarily is brought about as follows: A spring 37 tends to elevate the frame 35 and the parts carried 105 thereby. This tendency is resisted by a bar 38 fixed to the cross bar 22 of the platen frame and extending substantially throughout the length thereof. A roller 39 carried by the frame 35 bears up against the lower 110 edge of the bar 38, being pressed up against the bar by the spring 37. Ordinarily the roller 39 will follow the up and down movements of the bar 38 when the platen is shifted to upper and lower case positions, 115 and thus cause the normal position of the vibrator to be shifted accordingly. However, in the present construction there is no such case shifting movements of the parts, so therefore the parts normally will be retained in the Fig. 1 position, with the roller 39 pressed up against the bar 38 by the 120 spring 37.

In order to give greater access to the front of the platen for positioning other parts at 130

this point, as will hereinafter appear, it is desirable at times to lower the ribbon vibrator from its normal position. This is accomplished in accordance with the present invention as follows:

A bracket arm 40 is secured to and projects upward and forward from the frame 35, and at its upper end carries an anti-friction roller 41. A bar, plate, or controlling member 42, which extends substantially throughout the length of the carriage, has its rear edge portion secured, at 43, to a rock shaft 44. This rock shaft is mounted at its ends in bearing openings in the end plates 20 and 21 of the platen frame, and its rocking movement is controlled in a manner to be hereinafter pointed out. The forward edge of the plate 42 is bent down to form a flange 45 that is adapted to coact with the anti-friction roller 41 and move the frame 35 together with the parts carried thereby, or connected therewith, down from the Fig. 1 to the Fig. 3 position when the forward edge of the plate 42 is lowered. The effect of this is to lower the ribbon vibrator 30 from its normal Fig. 1 position, to a position such as is represented in Fig. 3, thus moving the ribbon vibrator out of an obstructing position where, as the parts are shown herein, it would interfere with the movement of certain parts employed to facilitate the rearward introduction of work sheets from the front of and beneath the platen, as will presently appear.

Coming now to the means for controlling and guiding the work sheets, it will be observed in the first place that there are no paper feed rollers employed beneath the platen, such feed rollers as are employed being located above the printing line; leaving the space beneath the platen free for the use of other devices.

There are two curved paper deflectors 46 and 47 employed beneath the platen, one arranged above the other and maintained spaced apart by intermediate spacing members or blocks 48 and 49 located near the ends thereof, as shown in detail in Fig. 13. Generally speaking these deflectors beneath the platen conform to the curvature of the latter, or are substantially concentric therewith, and extend substantially throughout the length of the platen. As thus constructed there are two separate channels provided, one of which is the open channel 50 between the two deflectors, and which is bounded at its ends by the separating members 48 and 49, either or both of which may constitute side guides or gages for co-operation with a work sheet or sheets introduced into the channel 50. The other separated channel 51 is provided between the under surface of the platen and the upper deflector 46. It will be seen from an inspection of Figs. 1, 8 and 12 that the forward edge of

the deflector 47 terminates in advance of the forward edge of the deflector 46, and that said edge portion has a slight downward curve in cross section. The deflector 47 is continued up at the rear to form an upwardly and rearwardly extending paper table 52, which terminates at 54 at a considerable height above the platen. On the other hand, the deflector 46 terminates in the rear of the platen at a much lower point and below the top of the platen, where it is bent to form a loop 55 that loosely surrounds a rod 56 fixedly connected at its ends to the end plates 20 and 21 of the platen frame. In this manner the rigidly united deflectors 46 and 47, together with all of the parts carried thereby, are mounted on the rod 56 and have a slight pivotal movement around said rod. The construction is such that the heavier parts connected to the paper deflectors in the rear of the pivot rod 56 cause the forward edge portion of the deflector 46, normally, to be lightly pressed against the platen, or against the interposed sheets R R'. In this manner the sheets R R' are held snugly against the platen and sheets I, L L' intended to be introduced rearwardly into the channel 50 are prevented from entering the channel 51. By moving the upper end of the paper table forward, the forward end portions of the deflectors may be moved downward a limited distance, thus carrying the forward contact edge of the deflector 46 away from the platen, all as provided for in the construction disclosed in the hereinbefore mentioned Hart application.

Certain adjustable work sheet gaging means, or paper end stops, which coact with the bottom edge of a ledger sheet L introduced through the channel 50, are supported on the paper table 52 and contribute to the preponderance of weight back of the pivot rod 56, spoken of above. These devices are the invention of Cloyd E. Burns and are claimed in a separate application filed by him July 13, 1926, Serial No. 122,239, but are disclosed herein in order to arrive at a better understanding of certain features of the present invention employed in connection therewith. These adjustable end stop devices which coact, in the present example, with the ledger sheet, are constructed as follows:

Upright bars 57 are fixed at 58 to the back of the paper table 52, and extend upward beyond the upper end 54 of the table through openings 53 (Fig. 13) in the upper bent portion thereof. These bars are connected at their upper ends to a cross bar 59 by suitable connecting means. Such connecting means comprise headed bolts 60 and nuts 61. Each associated pair of bolts 60 also pass through openings in a downwardly extending inclined bar 62 to firmly connect the latter to, and support it wholly at its upper end by,

- the associated bar and cross bar 59. Each bar 62 overlies its associated bar 57, and is spaced apart therefrom to form an intervening channel 63. Each channel 63 is bounded 5 on the rear side by the paper table 52 and a bar 57, and on the forward side by the overlying bar 62. Each channel 63 at its lower end communicates with the channel 50 intermediate the deflectors 46 and 47. It will 10 be seen that the lower unsupported end of each bar 62 passes down and is bent forward behind the pivot rod 56, and terminates in a bevel face 64 on its rear side where it enters the channel 50. This is to insure a 15 sheet introduced into the channel 50 from the front of the platen, passing from the channel 50 up through the channels 63 between the parallel bars 57 and 62 until arrested by an end stop 65 in the path thereof. 20 The end stop 65 is formed as a flange extending at right angles to the plane of a sheet metal bar 66 which extends between the upright bars 62 and is formed at its ends with guide loops 67 (see Fig. 11) which surround the bars 62. The stop bar 65—66 is 25 thus mounted for up and down adjustment on the bars 62 and may be retained in any position to which it is thus adjusted by set screws 68. Each screw is received in a 30 tapped opening in the associate loop 67 and bears at its inner end against the forward face of the bar 62 received in said loop. It will be seen that the stop face or flange 65 extends in the path of the bottom edge of 35 each ledger sheet L guided rearwardly and upwardly through the channels 50 and 63 and effectively arrests said sheet. 40 When the lower edge portion of each ledger sheet L is to be brought to the printing line, in order to write at and near the bottom of the sheet, the range of adjustment of the bar 66 is insufficient to bring the stop 65 to a position where it will coact with the bottom edge of the sheet. Therefore, in 45 accordance with the invention of the said Burns application, auxiliary end stops have been provided which will now be described. 50 It will be seen that two thin flexible or resilient metal arms 69 are pivoted at 70 on the front face of the bar 66. The pivotal mounting of these arms provides sufficient friction to hold the arms in either of the two positions to which they may be swung around their pivots, i. e., either to the ineffective 55 position, shown in Fig. 2, where the arms overlie the bar 66, or to the effective position, shown in Figs. 11 and 12, where they extend down at substantially right angles to said bar 66. The free end of each 60 arm 69 is bent at right angles to the bottom portion thereof to form an end stop 71 against which the bottom edge of a ledger sheet L is adapted to abut when the arms are in effective position. From an inspection of Fig. 12, it will be seen that by rear- 65 son of the flexible character of the arm 69 they may be bent to conform to the general contour of the deflectors 46 and 47, so that the stops 71 may be adjusted around the platen in the channel 50 by an adjustment of 70 the bar 66 in its lower positions along the bars 62. In this manner the auxiliary stops 71 may be brought into use to coact with the bottom edge of a work sheet L when said edge is within the channel 50 and beyond 75 the range of the stop 65, as shown in Fig. 12. 80 In the present example, assume that the ledger sheets L are in the nature of printed blanks with separate spaces for various entries thereon, some at least of which are written thereon through an interposed carbon sheet L', or in some instances each bill sheet L may have a carbonized back which would answer the same purpose. Also assume that each ledger sheet has printed thereon the months of the year, or the months of more than one year. If, for example, the entries are to be made near the top of each ledger sheet in an appropriate 85 cross line for the month of, say, January, then the operation will be as follows: The first ledger L is introduced rearwardly, as previously described, and accurately positioned with reference to a line finder or indicator, to be hereinafter described. When 90 this position has been attained, the end stop 65 is adjusted to coact with the bottom edge of the ledger sheet L, as shown in Fig. 9, and all successive ledger sheets adjusted to 95 said end stop 65 will be accurately positioned 100 to receive the "January" entries. When entries are to be made for the next month, "February", the first sheet will be positioned with the aid of the line indicator and the 105 stop 65 is adjusted as previously described, and all successively introduced ledger sheet L may be quickly and accurately introduced to properly receive entries for that month, and so on for succeeding months. 110 In order to facilitate the backward introduction of work sheets into the channel 50 from in front of the platen, there is provided a guide, shield or paper deflector 72 that is movable on the carriage from a substantially horizontally disposed ineffective 115 position, shown in full lines in Fig. 1, to a downwardly and rearwardly inclined effective position, shown in Fig. 3, and vice versa, as disclosed in said previously filed 120 Hait application. In order to receive these movements the deflector, in accordance with our invention, is constructed and mounted in the present instance as follows: The sheet metal deflector 72, which extends substantially throughout the length of the platen, 125 is bent under along one edge portion to form a looped or doubled portion 73 which extends throughout its length on the side thereof opposite its contact face, forming an en-

closed channel within the looped portion. This not only gives additional strength and rigidity to the deflector but facilitates manufacture and enables the deflector to be readily mounted. Thus, a deflector of the requisite length, depending on the length of the carriage employed, may be cut from a long folded strip. In the open ends of the channel formed by the looped portion of the deflector (Fig. 14) are received oppositely directed ears or bent ends 74 which project inwardly from parallel sheet metal arms 75 and 76 and are riveted to the deflector 72. These arms 75 and 76 are pivotally mounted respectively on forwardly projecting arms on the end plates 20 and 21 of the platen frame. The arm 76 carries a fixedly connected sleeve or hub 77, received and adapted to turn on an inwardly extending pivot pin 78 carried by the end plate 21. A coiled expansion spring 79 surrounds the pivot 78, pressing at one end against a shoulder 80 on the pivot and at its opposite end against the arm 76. The power of this spring tends to force said arm 76 and the parts connected therewith axially of the pivot 78, from the dotted to the full line position, for purposes which will presently appear. The arm 75 receives a pivotal support on the shouldered bearing portion 81 of a headed pivot screw 82, received at its threaded end in a supporting stud 83 that is secured to and projects inwardly from the end plate 20. An actuating arm, member or lever 84 has a hub 85 fixed thereto that receives a pivotal bearing on the reduced portion 86 of the pivot screw 82, and is confined against axial movement thereon by the end of the stud 83 and the shouldered portion 81 of the screw. The arm 84 carries a laterally projecting connecting pin 87 riveted thereto and projecting inwardly therefrom. This pin is adapted to be seated in a registering opening 88 in the arm 75 when the parts are in the full line position shown in Fig. 14. At this time the arms 84 and 75 are locked to turn together around the pivot bearings 86 and 81 respectively and to move the deflector 72 from the ineffective, Fig. 1 position, to the effective, Fig. 3 position.

It will be seen that the axial extent of the shouldered or bearing portion 81 of the screw 82 is such that the arm 75 may be shifted independently of the arm 84 from the full to the dotted line position in Fig. 14 against the force of the spring 79. When thus moved the arm 75 is disconnected from the pin 87, and from the actuating mechanism for the deflector 72. The latter with its supporting arms 75 and 76 is then free to drop or turn forward and downward from the substantially horizontally disposed full line position, shown in Fig. 1, to the substantially vertically disposed dotted line

position. This is to give more ready access to parts arranged below the deflector 72 and between it and the platen, and is available more particularly to enable the ribbon 30^a to be readily threaded through the ribbon 70^a vibrator 30, etc.

Ordinarily, as when the machine is in use, the deflector 72 is maintained in the full line Fig. 14 position by the spring 79, where it remains connected to the actuating arm 84. This arm is connected and actuated, in the present instance, as follows; it being understood that the deflector normally occupies the ineffective, full line position shown in Fig. 1. The outer end of the rivet which carries the pin 87 (Fig. 14) is headed at 89, and has a shouldered bearing 90 for pivotal connection to the rear end of a link 91. As best seen in Fig. 6, the forward end of the link 91 is pivoted at 92 to the lower arm 93 of a lever 94 of the first order, pivoted to the carriage and having an upper arm 95. As shown in Fig. 7, the lever 94 has a hub 96 fixed thereto. This hub turns on a fixed pivot rod 97 supported at its ends in fixed bracket arms 98 and 99 secured to the carriage. The end of the pivot rod 97 which is supported in the bracket arm 98 is slabbed-off at 100, where it is received in a correspondingly shaped opening in said bracket arm to hold the rod against turning; a screw 101 holding the rod on the bracket arm. The upper arm 95 of the lever is pivoted at 102 to a rearwardly extending link 103, which in turn is pivoted at its rear end, at 104, to a curved lever or crank arm 105. This arm at its upper end terminates in a finger piece 105^a, by which it and the parts connected therewith may be actuated. As best shown in Fig. 5, the lower end of the crank arm 105 is provided with a hub 106 fixed to the rock shaft 44 which, as hereinbefore indicated, extends across the carriage and is supported at its ends in bearings in the end plates 20 and 21. As shown in Figs. 5 and 6, the left-hand end of the shaft 44 extends beyond its bearing and is slabbed-off at 107, for reception in a corresponding opening in a crank arm 108 having a laterally extending projection or lug 109. This arm is secured in place on the shaft 44 by a nut 110 threaded onto the left-hand free end thereof. The lug 109 is notched in its forward edge to receive the free end of a wire spring 111. This spring is coiled around a pin 112 and anchored at its opposite end on a screw 113; the pin 112 and screw 113 projecting outwardly from the end plate 20 of the platen frame. The force of the spring 111 is exerted to return the rock shaft 44 and the parts connected therewith to normal position, shown in Fig. 1, where they are arrested by an inwardly projecting lug 105^b on the arm 105 coacting with the face of the platen near the left-hand end thereof.

The opposite end of the rock shaft 44 carries a crank arm 114 (Fig. 2) similar to the crank arm 105 except that there is no finger piece 105^a or lug 105^b, thereon, and there is no train of connections between the arm 114 and the deflector 72, as exists between the arm 105 and said deflector.

Each of the crank arms 105 and 114 carries a member or carrier 115 adjustably mounted thereon by any suitable means. As shown in Fig. 6, each member 115 consists of a plate slotted lengthwise, or up and down, at 116 to receive the stems of headed screws 117 threaded into tapped openings in the associate arm 105 or 114. By loosening the screws 117 the plates 115 may be adjusted up or down, and a tightening of the screws will cause the heads thereof to bind against and hold the plates in their adjusted positions. Each plate is apertured to receive the end of a relatively fine wire line gage or indicator 118 therethrough. The wire is drawn taut in a straight line between the plates 115 and is headed or bent at each end, as indicated at 119 in Fig. 5, to prevent it from being drawn through the apertures in the plates 115. As thus mounted the fine wire line indicator may be adjusted up and down on the arms 105 and 114 to different set positions in order that an accurate registration with the printing line may be effected when said arms hold the line indicator in the indicating position, shown in Fig. 1.

For reasons which will hereinafter more clearly appear, it is desirable at times to have the line indicator register with top edges of previously written characters, or to indicate where the top edges of the characters will appear on a sheet, as indicated in Fig. 19, as well as to register at other times with the bottom edges of previously written characters, as indicated in Fig. 20. By making the diameter of the wire line indicator materially less than the height of a character to be written, as indicated in these figures, the line indicator may be used in the manner described, it being understood that the indicator cannot obscure any of the written characters beneath or below it.

In accordance with our present invention we have embodied, in addition to the end stops 65 and 71, a set of automatically controlled end stops 120 to coat with the bottom edge of, say, a bill sheet I, and more particularly available for use where more than two work sheets are to be introduced in correlation in the machine, as supposed in the present instance. Or, in other words, where more than one work sheet is to be introduced rearwardly through the channel 50 for each writing operation, one being a comparatively long sheet, as L, and the other a comparatively short sheet, as I, it is desirable to employ the automatically controlled stops in addition to the other

end stops described. Each of the stops 120 is formed at the end of an arm 121 which has a hub 122, (shown in dotted lines in Fig. 2), secured to a rock shaft 123 by a set screw 124. There may be any suitable number of these stops 120, three being shown in the present instance. Each stop moves through a registering opening 125 in the lower deflector 47 from an effective position in the channel 50, as shown in Fig. 1, to an ineffective position out of said channel and below the deflector, as shown in Fig. 3. It will be seen that at no time will these stops coat with an end of a work sheet except the sheet be introduced rearwardly through the channel 50, and even then, of course, only when the stops 120 are in their normal or effective position. The shaft 123 on which these stops are supported is mounted at its ends in bearing openings in the end plates 20 and 21 of the platen frame. This shaft is surrounded near the right-hand end thereof (see Fig. 2) by a coiled spring 126 connected at one end to the end plate 21, and at its opposite end to a collar 126^a, held by a set screw to the shaft. The power of this spring is exerted to turn the shaft clockwise, as viewed in Fig. 1, and normally retain the stops in the effective position, as there shown. Near the opposite end of the shaft is secured a controlling arm or member 127 (see Fig. 66) which terminates at its forward end in a key 128. This arm has a hub 129 secured to the shaft by a set screw 130. Offset inwardly from the arm 127 is a lug 131 (see Fig. 5) which extends beneath and in the path of the pivoted arm 105. The downward motion of the arm 127 is limited by the stud 83 by which the deflector 72 is pivotally supported at one end, whereas the upward movement of the arm 127 is limited by the lug 131 contacting with the arm 105. From the foregoing description it will be understood that when the parts are in the normal, Fig. 1, position the finger piece may be actuated at any time to move the stops 120 to the Fig. 3 ineffective position. This movement of the stops 120 is independent of the automatic operation of said stops effected in a manner to be hereinafter described.

Briefly the operation of the parts thus far described is as follows:

A movement of the finger piece 105^a from the Fig. 1 to the Figs. 3 and 6 positions results in lowering the ribbon vibrator 30 out of the way through the operation of the plate 42; in shifting the stops 120 to ineffective position; in shifting the line indicator 118 to ineffective or non-indicating position; and in shifting the front deflector 72 from the inoperative or ineffective, full line Fig. 1, position, to the effective or operative position shown in Figs. 3 and 6. It will be seen from a comparison of these fig-

ures that this shifting of the deflector 72 carries it from the full line Fig. 1 position, where it is out of the path of the types 27, to the Fig. 3 position, where it is interposed 5 in the path of said types and crosses the printing line. This shifting of the deflector 72 changes its angular position, as well as effecting a bodily movement thereof, so that when it reaches the Figs. 3 and 5 position 10 it will overlap the front edge of the deflector 47 and practically form a continuation of the channel 50. With the parts disposed in this position, a work sheet L may be readily introduced from the front of the 15 platen and shifted rearwardly beneath the latter through the channels 50 and 63 until the bottom edges of the work sheet reaches the end stop 65 or the stops 71, as the case may be. Assuming that the bar 66 has been 20 previously adjusted to the proper position, the work sheet L will be properly positioned to receive a line of imprints on the proper cross-line thereof after the feed rollers, to be hereinafter described, are rendered 25 effective to clamp the sheet against the platen. When the finger piece 105^a is released by the operator the various parts referred to will be returned to normal Fig. 1 position by the springs 126, 111 and 37. 30 It will be seen that the movement of the end stops 120 under control of the key 128 is effected independently of the movement of said stops automatically under control of the finger piece 105^a. It also may here be 35 pointed out that the movement of the parts described above under control of the finger piece 105^a is effected independently of an automatic shifting of said parts by a shifting operation of certain of the paper feed 40 rollers, as will presently appear.

We will now describe the construction and arrangement of the form of paper feed roller mechanism disclosed in said Hart application and which is used in conjunction 45 with the devices of our invention, as well as the means whereby a shifting of certain of said feed rollers automatically brings about a shifting of other of the parts hereinbefore described.

50 Referring more particularly to Figs. 1, 2 and 15, it will be seen that a cross bar or pivot rod 133 extends throughout the length of the carriage in the rear of the paper table 52, and is secured and held against turning 55 movement at its ends to the end plates 20 and 21 of the platen frame by screws 134. Loosely supported on the left-hand end portion of the rod 133 is an elongated hub or bearing sleeve 135 of a forwardly extending supporting arm 136 which is fixed to the hub. A spacing washer 136^a maintains the arm 136 separated from the end plate 20. A coiled spring 137 surrounds the hub 135 and rod 133 and is fixed at one end to a collar 60 138 on the rod 133. Said collar is held in position on the rod by a set screw 139. The other end of said spring is connected to the supporting arm 136, so that the force of the spring is exerted to move said arm downward around the pivot rod. An adjustment 70 of the collar 138 to different set positions around the pivot rod 133 is effective to increase or decrease the force of the spring 137 on the arm 136, depending on the adjustment of the collar in one direction or the other around said rod, thereby giving an individual tension adjustment for said arm. The arm 136 extends forward over the platen and is provided with a bearing opening 140 that receives the reduced end 141 75 of the cross bar 142 on which paper feed rollers 143 are mounted to turn. A shouldered headed screw 142^a is threaded into a tapped opening in the left-hand end of the rod 142 to prevent a disconnection of the rod from its arm 136. It will be seen from Fig. 15 that the head of the screw 142^a does not bind against the side of the arm 136. The opening 140 in which the reduced end 80 of the rod 142 is received is large enough to enable the rod 142 to assume different angular relations to the arm 136, for purposes which will presently appear. The manner of mounting the arm 136, individually adjusting its spring 137, and connecting said 85 arm to one end of the roller supporting rod 142, etc., is duplicated at the other end of said rod. Corresponding reference numerals will therefore be used to designate the 90 corresponding parts at the other end of the rod. The rather loose mounting of the roller bearing rod 142 in the bearings 140 in the supporting arms 136 enables said rod to change its angular relation to said arms 95 so that it may assume a position out of exact 100 parallelism with the axis of the platen shaft. This construction enables each spring 137 to apply its force individually to the associated end of the roller carrying rod 142, and to the roller 143 nearest said end, and effect 105 an accurate feed of the work sheet R and companion carbon sheet R' under varying conditions of use, and cause a substantially equal pressure to be exerted by said rollers, even though a greater thickness of paper be 110 fed under one roller than under the other.

Suitable means are shown to enable each feed roller 143 to be adjusted to different 115 positions along the shaft or rod 142 to accord with the width of the work sheet R, and corresponding carbon sheet R', with which the feed rollers 143 coact, preferably at and near the margins thereof. Thus, as seen in Fig. 15, a small coiled spring 144 surrounds the shaft 142 and has a friction-tight binding action thereon, and is contained loosely within a chamber 145 in the bearing member 146 of the companion rubber covered feed rollers 143. The spring 120 retains the roller in the position to which 125 129

it is adjusted along the rod 142, while allowing the roller to turn freely.

By swinging the rod 142 and arms 136 upward and rearward away from the platen 5 and around the pivot rod 133, the leading edges of the sheets R and R' may be readily introduced beneath the feed rollers 143. The operator then releases the parts and said feed rollers will press the sheets R and 10 R' against the platen, to the exclusion of all other sheets introduced in the machine, as indicated in Figs. 6 and 10.

In order to accurately position the sheets R and R' widthwise in the carriage, we have 15 provided an adjustable side edge gage 147 with which the left-hand edges of said sheets may be brought into register, as shown in Fig. 2. From an inspection of Figs. 1 and 2 it will be seen that the inner 20 contact face of the blade-like member or gage 147 extends in a plane at right angles to the axis of the platen. Said member is carried by a hub 148 mounted on and adjustable along the roller carrying rod 142. 25 A thumb screw 149 is received in a tapped opening in the hub 148 and bears at its inner end against the rod 142 to hold the gage in its adjusted position.

In addition to the paper feed rollers 143 30 there is employed, as in the construction disclosed in said Hart application, one or more sets of feed rollers depending on the use of the machine as a "two-sheet biller" or for more than two work sheets. The construction in the present instance is shown and 35 specifically described in one example of its use as a "three-sheet" biller and consequently we have illustrated two additional sets of paper feed rollers 150 and 151. These 40 rollers are shown arranged above the printing line and are in the nature of two sets of margin feed rollers located in axial alignment forward of the feed rollers 143. The feed rollers 151 are more widely separated 45 than the rollers 150, and are intended to cooperate only with the wider ledger sheet L in the example shown, whereas the rollers 150 coact, in the example shown, with the narrower bill sheet I. One or more sets of 50 these rollers may be employed depending on the requirements, and they may be mounted in any suitable manner to attain the ends in view. As shown in the present instance, these paper feed rollers are mounted for individual adjustment longitudinally of the 55 platen; they are arranged so that the rollers of each set or pair may be shifted in unison into and out of contact with the platen or the work sheet with which they coact; they are arranged so that the rollers of either set 60 may be shifted in unison independently of the rollers of the other set, or the rollers of both sets may be shifted in unison at a single 65 operation.

The construction also includes means

whereby the parts hereinbefore described, such as the ribbon vibrator, the deflector 72, the line indicator 118, end stops 120, etc. are automatically controlled by the shifting of one of the sets (151) of feed rollers (150 70 and 151) into and out of effective position, all of which will hereinafter more clearly appear.

In the present instance each of the feed rollers 150 or 151 is pivotally supported in 75 a yoke-like carrying member 152, 152^a, 152^b or 152^c pivotally mounted on the pivot rod 97, hereinbefore described, to swing thereon and thus carry the companion feed roller into and out of effective position. Suitable 80 individual detent or holding mechanism is employed to hold each roller in either of such positions and cause the roller to bear, with a spring pressure, against the work sheet when the roller is in effective position. 85

The detent mechanism in question is in each case similar to that disclosed on a large scale in Fig. 7, from which it will be seen that a collar 153 surrounds the pivot rod 97 intermediate the arms of the yoke and is secured to the rod by a set screw 154. An adjustment of the collar 153 along the pivot rod with the yoke determines the position of the companion feed roller longitudinally of the platen, and when the set screw 154 is 95 tightened axial movement of the collar and its companion yoke is prevented without interfering with the pivotal movement of the yoke. A follower 155 is slotted at 156 on opposite sides thereof to receive the pivots 157 of a small metal detent roller 158. The pivots 157 slide as well as turn in bearing slots 159 in the arms of the associated yoke. A leaf spring 160 is attached intermediate 100 its ends, at 161, to the follower 155, whereas the outer free ends of the spring bear against the end walls of the bearing slots 159. From an inspection of Fig. 1, it will be understood that the lower rear side of each collar 153 is slabbed off at 162 forming an 110 inclined contact face with which the companion detent roller 158 coacts when the associated feed roller is in effective position. This causes the companion spring 160 to exert its individual force with considerable 115 pressure on the associated feed roller. When, however, the yoke is swung up to release the feed roller the detent roller will bear against the cylindrical periphery of the collar 153, or in some cases in a notch or 120 groove 153^a or 153^b formed therein to retain the yoke in the definite predetermined position to which it may be shifted and resist the reaction of certain returning springs as 125 will presently appear. The detent mechanism described above is substantially the same for each of the feed rollers 150 and 151 except, as indicated above, that in some instances, as for the left hand yoke 152, retaining grooves 153^a and 153^b are provided 130

in collar 153 for cooperation with the roller detent 158. Therefore, the same reference characters are employed to designate the different detent devices. The yoke of each feed roller 150 and 151 is much the same except for the yoke 152^a. This yoke for the right hand roller 151 may have its side arms brought together and united at 163 as shown in Fig. 1. This is in order to give greater visibility to the right hand exposed margin of the work sheet L.

In order that each companion pair of these feed rollers 150 and 151 may be shifted into and out of effective position in unison and by a single operation without, nevertheless, impairing the individual spring pressure of the feed rollers on the platen there is provided in the construction the following described means:—

Referring more specifically to Figs. 1, 16 and 17 it will be seen that the cross bar of each yoke or feed roller carrier is provided with a forwardly projecting headed pin 164. A sheet metal, slightly flexible or resilient, connecting bar 165 is bifurcated or slotted at its ends, as indicated at 166, to receive the stems of the pins 164 on the yokes of the companion pair of feed rollers 150 or 151. The end yokes 152 and 152^a extend further forward than the intermediate ones, 152^b and 152^c, so that one set of yokes, and the connecting bar 165 therefor, will not interfere with the pivotal movement of the yokes and bar of the other set. It will be understood that the bars 165 may be readily connected to or detached from their respective carriers or yokes, and that bars of different lengths may be employed, depending on the adjustment of the yokes along the pivot rod 97, or the distance that the rollers of each pair are to be maintained spaced apart on the pivot rod. In Figs. 16 and 17 there is illustrated different relative adjustments of the feed rollers and yokes, the connecting bars 165 in Fig. 17 being shorter than the corresponding bars in Fig. 16.

The left hand yoke 152 is provided with an upwardly extending arm 167 which terminates in a laterally projecting finger piece 168, as best shown in Figs. 1 and 2. A corresponding arm 169 and finger piece 170 is fixed on the left hand yoke 152^a of the other set. As shown in Fig. 2, the arms 167 and 169 are secured on adjacent arms of the two left hand yokes 152, 152^a, and the two finger pieces 168 and 170 project outwardly away from each other. This permits, when desired, an adjustment of the two left yokes in close relationship. Such an adjustment is not always necessary or desired, and where the two left hand rollers are to be maintained more widely separated, as shown in Fig. 4, then the finger pieces may be extended towards each other, as indicated at 168^a and 170^a in Fig. 4. In either event,

however, the finger pieces are arranged in such close relationship, one to the other, that they may be simultaneously grasped by one hand of the operator, if desired. It is, therefore, easy to turn both yokes to which the finger pieces are connected to an upright position, carrying the companion feed rollers to ineffective position and transmitting motion through the connecting bars 165 to the other yokes, and thus effect a simultaneous shifting of all four feed rollers 150 and 151 away from the platen. On the other hand, a shifting of the finger piece 168 merely results in shifting both feed rollers 150, and a shifting of the finger piece 170 results in a shifting of both feed rollers 151 independently of the feed rollers 150. The slight resiliency in each of the bars 165, while not interfering with the independent spring pressure applied to each of the feed rollers 150, 151, by its spring 160, nevertheless causes both feed rollers operatively connected by each bar 165 to be thrown off together, or substantially in unison.

The locking groove 153^a in which the associated detent roller 158 is seated when the yoke 152 is in the thrown-off upright position more effectively holds said yoke and the parts automatically controlled thereby, in their actuated positions and against the reaction of the returning springs 37, 111 and 126, as will presently more clearly appear. On the other hand, the locking groove 153^b, and associated detent roller, hold the yoke 152 and the feed rollers 151 controlled thereby in the intermediate Fig. 8^a position and as shown in dotted lines in Fig. 1.

From an inspection of Figs. 1, 3 and 8^a it will be seen that the inner arm of the yoke 152 carries a depending left-hand side edge gage 171, the plane of which is at right angles to the axis of the platen. When the parts are in and near the normal position, as shown in Fig. 1, the edge 172 of this gage lies close to the platen, and the gage will contact with the left hand side edges of the work sheet I and the companion carbon sheet I', as indicated in Fig. 2. This provides means for accurately positioning these sheets lengthwise of the platen and in proper relation to other sheets in the machine.

The control of the deflector 72, line indicator 118, ribbon vibrator 30, stops 120 etc., is automatically effected by a shifting movement of certain of the above mentioned feed rollers by the following means: Referring particularly to Figs. 1 and 3 it will be seen that the actuating link 103 carries an upstanding ear 173 from which an inwardly extending pin 174 projects. This pin overlies and extends in the path of the left hand arm of the yoke 152 as said yoke is moved from the normal, full line Fig. 1 position, to the Fig. 3 position to release the feed rollers 151. There is a lost motion of said arm

before the pin is picked up, for purposes which will presently appear. However, when the arm in question reaches the pin the latter will continue its movement with the arm, shifting the link 103 and the parts connected therewith from the Fig. 1 to the Fig. 3 position. The effect of automatically actuating the link 103 in this manner is the same as operating the finger piece 105 to the limit of its operating movement. This, as previously described, results in lowering the ribbon vibrator, in shifting the end stops 120 to ineffective position, in moving the line indicator to non-indicating position and in moving the deflector 72 to effective position, all as shown in Fig. 3. The parts will be held in such positions under the action of the companion spring pressed roller detent 158 in the groove 153^a, and against the reaction of the springs 37, 111 and 126, until the margin feed roller 151 are again returned by hand to effective position. The parts in question will then be returned to their normal positions disclosed in Fig. 1 by their respective springs 37, 111 and 126.

While, as has previously been pointed out, the machine may be used differently under different conditions, we will continue the assumption of a condition of use hereinbefore pointed out, in which a record or register sheet R, a carbon sheet R' therefor, a ledger sheet L, a carbon sheet L' therefor, and a bill sheet I, are employed to be simultaneously written on, with possible additions made directly in the right-hand margin of the sheet L only. In some instances a protecting sheet (not shown) is employed in front of the carbon sheet R', but this is not absolutely necessary and is ignored in the present instance. Assuming that the margin feed rollers 150 and 151 are in the upright ineffective position, the record sheet R and its carbon sheet R' of the same size (placed with its transfer face next to the record sheet) are first introduced together from the rear of the platen through the channel 51. These sheets are positioned widthwise by bringing the left hand side edges of said sheets against the adjustable side edge gage 147, and their leading ends are inserted beneath the feed rollers 143 which alone contact directly with the sheet R. The positions of the parts at this time are diagrammatically illustrated in Fig. 8. In thus introducing the sheets R and R', they may be fed forward or back with the aid of the platen 19 and feed rollers 143 and if necessary properly adjusted with reference to the printing line. If desired, the line indicator 118 may be used in aiding in the adjustment of these sheets or any sheets with which the rollers 143 may be used to coact. In order that the line indicator may be temporarily used at this time, the

finger piece 170 is employed to move the feed rollers 151 down to the position indicated in Fig. 8^a where they are retained free from the platen by the associated detent 158 seating itself in the locking groove 153^b, as indicated. By reason of the lost motion between the feed roller carrier or yoke 152 and the pin 174 this is the point where in the releasing motion of said carrier the pin 174 is picked up. It follows, therefore, that at this time, the line indicator 118, the deflector 72, the stops 120 and the ribbon vibrator 30 are all in their normal positions, as shown in Fig. 8^a with the line indicator in position for use in front of the sheets R R'.

Next the ledger sheet L is introduced rearwardly through the channel 50, but before doing this the feed rollers 151 are returned to the Fig. 8 position, thereby automatically restoring the deflector 72 and other parts mentioned above to the Fig. 8 position, leaving the channel 50 open and the parts positioned to readily receive the backwardly introduced ledger sheet. As the ledger sheet is then inserted backwardly it will be guided up in the rear of the platen between the parallel bars 57 and 62, and with the left-hand side edge of the sheet against the side wall 48 of the channel 50, the sheet will be accurately positioned widthwise with reference to the platen and the previously introduced register sheet R and its carbon sheet R'. Then by moving the rollers 151 down to Fig. 8^a position the line indicator may be rendered effective to obtain initially the proper adjustment of the ledger sheet L in the line space direction. This is attained with the aid of the line indicator 118 by registering, say, the line dividing the first cross column from the printed headings with the line indicator, to write below said indicator in the first or "January" cross column. The margin feed rollers 151 are turned down into effective position to coact with the marginal portions of the sheet L, the parts at this time being disposed as indicated in Fig. 9. The end stop 65 is then adjusted down to a position where it will coact with the bottom edge of the ledger sheet, as shown in Fig. 9. All succeeding ledger sheets L introduced into the machine during, say, the same month, may then be quickly and accurately positioned in a line feed direction with the aid of the end stop 65 and without using the line indicator. A single adjustment of the latter in the manner described for the next month will suffice for all of the ledger sheet entries to be made in that month.

Now in introducing a bill sheet I, which is usually of considerably less length than the record and ledger sheets, a carbon sheet L' of the same length and width as the bill sheet may be introduced with the latter. That is true unless the bill sheet has a car-

bonized back, in which instance no carbon sheet L' is required.

With the sheets R , R' and L held in position by their respective feed rollers 143 and 151, as shown in Fig. 6, the bill sheet I and carbon sheet L' may be readily introduced downwardly and rearwardly from in front of the platen into the channel 50. At this time the parts are in the position indicated in Fig. 6, being temporarily moved to and held in such position by actuating the finger piece 105^a with one hand, while introducing the sheets I and L' into the channel 50 with the other hand. From the position of the parts indicated in this figure it will be seen that the ribbon vibrator has been lowered from its normal position shown in Fig. 1, that the line indicator 118 has been moved out of the way to an ineffective position, and that the deflector 72 has been moved to an effective position where it will aid in effectively directing the lower ends of the sheets I and L' into the channel 50. After introducing the work sheets into the channel, as indicated in Fig. 6, and releasing the finger piece 105^a, the parts will return to normal position, as shown in Fig. 10, positioning the end stops 120 in the effective position and thus enabling the said sheets I and L' to be adjusted against said stops for accurately determining the proper position of the sheets in the line feed direction. In order to attain the proper widthwise positioning of the sheets I and L' they may be adjusted to contact with the side edge gage 171, since at this time the rollers 151 are in the Fig. 6 position where said gage is effective. The feed rollers 150 are then moved down to effective position, clamping the sheets I and L' to the platen, as shown in Fig. 10.

The machine is now in condition to write the bill, and a manifold copy thereof will be written in its appropriate place on the ledger sheet through the interposed carbon sheet L' . A manifold copy will also be made on the record sheet R through the interposed carbon sheet R' . When the bill sheet is written, the feed rollers 150 and 151 are simultaneously swung upward to the upright ineffective position by the finger pieces 168 and 170, thereby releasing the sheets I , L' and L while the sheets R and R' remain clamped in position by their feed rollers 143. The act of throwing the feed rollers 150 and 151 to upright position not only frees the work sheets as described, but also results in moving the end stops 120, the ribbon vibrator 30 and the deflector 72 to the positions indicated in Fig. 3, thereby enabling the sheets I , L' and L to be readily withdrawn, leaving the sheets R and R' in the machine. The machine is conditioned to receive first a new ledger sheet L and then a

new bill sheet I , with an accompanying carbon sheet L' , in the manner hereinbefore indicated, and so on as successive bills are written.

It will be understood that in returning the carriage after the last line on a bill is written, the platen will be automatically line spaced, which will feed the record sheet R and companion carbon sheet R' forward one space ready to receive the manifold copy of the next bill entered on the record sheet.

When entries for the next month are to be made the first ledger sheet is positioned with the aid of the line indicator as previously pointed out. The end stop 65 is then lowered to contact with the bottom end of the adjusted ledger sheet, and is secured in that position. In all subsequent introductions of ledger sheets during that month they may be quickly and accurately positioned with the aid of the end stop 65 (or the stops 71 as the case may be) and side gage 48 with the assurance that the bills copied on each ledger sheet through the carbon sheet L' will be positioned in the proper blank or space therefor on the ledger sheet.

We have hereinbefore indicated that the present machine is capable of a very wide range of use, and may be employed with or without slight change in almost any character of billing or like work wherein two or more sheets are employed, and where one or more work sheets are introduced into and removed from the machine, while another or other sheets are retained in the machine and a certain correlation is required between the sheet or sheets retained in the machine and those introduced therein from time to time.

For example, let it be supposed that the machine is to be used as a check writing machine, in which a copy is to be made of all checks as they are written. In this event the checks only would be rearwardly introduced into the channel 50. It would be unnecessary in this event to automatically actuate the end stops 120. This might be readily provided for by removing the arm 127 or adjusting it on the shaft 123 to a position where it would not be actuated by the arm 105, in which event the end stops 120 would be constantly spring-pressed to operative position and remain there always ready to coat with the bottom edges of the checks to properly position them, assuming the location of the stops 120 to be a proper one for this purpose. Or, on the other hand, the arm 127 might be allowed to remain on the shaft as shown, and merely advance the end stops 71 to some such position as that indicated in Fig. 12, and permit them to remain in such position indefinitely. The record of the checks written would be manifolded through the carbon sheet R' to the record sheet R , both of which latter sheets are fed

through the separate channel 51. In this event the sheet R would constitute a "pay roll" or "register" sheet. There would be no necessity for the feed rollers 150 or the 5 end stop 65 in this use of the machine, and they may be removed, if desired, or allowed to remain in the machine out of use. When the end stops 71 are to be employed in this 10 use of the machine, as indicated above, the end stops 120 may be omitted or allowed to remain in the machine out of use; the use of the stops 71 providing for the adjustment thereof to accord with checks of different depths.

15 Generally speaking, the sheet R, if used in bookkeeping work with a ledger sheet, may constitute a so-called "register" or "proof sheet." If used when copying invoices, it may constitute a "sales sheet" or a "distributing sheet." If used in check writing it may constitute a "pay roll" or "register sheet." In each event, however, the sheets R R' remain in the machine while the remaining work sheets I and L (or either of them as the case may be) are removed after 20 each writing, and new sheets entered in place thereof.

One specific instance of the advantages of the use of the line indicator 118 to coat or 30 register with the tops as well as the bottoms of the written characters is given below.

In the #23 Remington bookkeeping machine, in which the present machine is embodied, as hereinbefore indicated, the carriage 35 is automatically returned at a predetermined point in its forward travel and the platen is automatically line spaced.

In using said machine in ordinary commercial bookkeeping, where a bill sheet and companion ledger sheet are written at one operation, the automatic return of the carriage and line spacing operation are effected at different predetermined points. In one case the return of the carriage is effected immediately after the "balance" is written (see Fig. 20) and consequently the carriage is to 40 the right, and the platen line-spaced when the next ledger sheet is introduced. In another case the new ledger sheet may be introduced while the carriage is at the left and before it is automatically returned. The different cases mentioned above depend on whether the "pick-up" column is on the right hand or the left hand side of the ledger sheet, both forms being indicated in Figs. 19 and 20. It follows, therefore, that in some 45 instances a bill sheet and corresponding ledger sheet will be inserted and positioned with the aid of the line indicator 118, and the "pick-up" written when the carriage is near the left-hand end of its travel, whereas in other instances, these sheets will be inserted and positioned, and the "pick-up" written, after the carriage has been returned to 50 the right, and the platen automatically line-spaced.

55 What we claim as new and desire to secure by Letters Patent, is:—

1. In a typewriting or like machine, the combination of a ribbon guide carried by the frame of the machine, a paper deflector shiftable into and out of effective position, and means operable at will for moving said 60

spaced. For this reason a newly inserted ledger sheet in one instance will be brought with the upper ends of the characters in the last previously written line on the sheet substantially in register with the line indicator, 70 whereas in another instance the lower ends of said characters will be brought substantially in register with the indicator. This is indicated in the concrete example illustrated in Figs. 19 and 20 in which the first 75 entry in each instance is indicated in dotted lines, and as is more fully set forth in said previously filed Hart application.

While we have rather elaborately shown and described a machine having various features of the construction which were not invented by us, as hereinbefore indicated, such features, nevertheless, enter into co-operation with the various devices of our invention and are therefore necessary to a 80 complete understanding of the present invention, the primary purpose of which was to improve said machine as it is embodied in the hereinbefore mentioned Hart application. In order to make the foregoing perfectly clear it may be pointed out that except for the specific construction of the deflector 72; the means whereby it may be detachably connected to its actuating means to permit the deflector to be dropped to the dotted line Fig. 1 position; the provision of the automatically actuated stops 120, and the means for independently actuating them; the provision of means for automatically moving the ribbon vibrator down to provide greater clearance for the movement of the deflector 72 to effective position; and the provision of the side edge gages 147 and 171, the construction disclosed herein 95 is not of our invention but is the invention of Frederick A. Hart, except the adjustable end stop construction which is the invention of Cloyd E. Burns. Such disclaimed mechanism is not claimed herein except in combination with devices of our present invention with which it coacts.

Various changes may be made in the construction, and certain parts thereof may be employed without others, without departing from our invention as it is defined in the accompanying claims. We are aware, moreover, that various features of our construction may be employed in combination with specifically different means from those disclosed herein for controlling the paper feed 100 rollers, etc. and therefore do not limit ourselves to the construction shown and described.

What we claim as new and desire to secure by Letters Patent, is:—

1. In a typewriting or like machine, the combination of a ribbon guide carried by the frame of the machine, a paper deflector shiftable into and out of effective position, and means operable at will for moving said 110

130

ribbon guide out of the path of said deflector in order to enable the latter to be shifted to effective position.

2. In a typewriting or like machine, the combination of a paper deflector shiftable into and out of effective position, a ribbon guide normally in an obstructing position in the path of said deflector, and automatically operating means for shifting said ribbon guide out of its normal obstructing position when said deflector is shifted to effective position.

3. In a typewriting or like machine, the combination of a ribbon vibrator, means for actuating said ribbon vibrator at each printing operation, a paper deflector shiftable into and out of effective position, and means for shifting said vibrator away from normal position when said deflector is shifted to effective position.

4. In a typewriting or like machine, the combination of a ribbon guide for interposing the ribbon in the path of the types, a paper deflector movable from an ineffective position out of the path of the types to a position in the path of the types where the deflector may aid in effecting a backward introduction of a work sheet across the printing line, and means for shifting the ribbon guide out of normal position by a movement of the deflector to effective position.

5. In a typewriting or like machine, the combination of a carriage, a platen carried thereby, a paper deflector carried by the carriage and extending longitudinally of the platen in front thereof and normally in ineffective position out of the path of the types but shiftable to effective position in the path of the types where it may aid in effecting a rearward introduction of a work sheet past the printing line, a ribbon vibrator, and means for automatically moving said vibrator away from normal position when said deflector is moved to effective position.

6. In a typewriting or like machine, the combination of a platen, two sets of feed rollers disposed at different points along the platen, the feed rollers of each set being shiftable towards and away from the platen independently of the feed rollers of the other set, stops for arresting the bottom edge of a work sheet introduced rearwardly around the platen from the front thereof, and automatically operating means controlled by the movement of one set only of said feed rollers away from the platen for positioning said stops in ineffective position.

7. In a typewriting or like machine, the combination of a platen, two sets of feed rollers disposed at different points along the platen, the feed rollers of each set being shiftable towards and away from the platen independently of the feed rollers of the other set, a paper deflector carried by the carriage in front of the platen to aid in in-

roducing work sheets from the front of the platen rearwardly around and beneath the platen, said deflector being shiftable from an ineffective to an effective position in which it is in the path of the types, stops 70 for arresting the bottom edge of a work sheet introduced rearwardly around the platen from the front thereof, and automatically operating means controlled by the movement of one set only of said feed rollers 75 away from the platen for shifting said stops to ineffective position and the deflector to effective position.

8. In a typewriting or like machine, the combination of a platen, paper feed rollers 80 shiftable towards and away from the platen, a paper deflector shiftable from an ineffective to an effective position where it will aid in introducing a work sheet rearwardly around and beneath the platen from the 85 front thereof, a line indicator shiftable into and out of effective position, stops for arresting the bottom edge of a work sheet introduced rearwardly around the platen from the front thereof, and automatically operating 90 means which by a movement of said feed rollers away from the platen causes the line indicator to be shifted to ineffective position, causes the paper deflector to be shifted to effective position, and causes the stops to 95 be shifted to ineffective position.

9. In a typewriting or like machine, the combination of a platen, paper feed rollers 100 shiftable towards and away from the platen, a paper deflector shiftable from an ineffective to an effective position where it will aid in introducing a work sheet rearwardly around and beneath the platen from the front thereof, a line indicator shiftable into and out of effective position, stops for arresting the bottom edge of a work sheet introduced rearwardly around the platen from the front thereof, automatically operating 105 means which by a movement of said feed rollers away from the platen causes the line indicator to be shifted to ineffective position, causes the paper deflector to be shifted to effective position and causes the stops to 110 be shifted to ineffective position, and means 115 operable at will independently of said movement of said feed rollers for effecting such movements of the line indicator paper deflector and stops.

10. In a typewriting or like machine, the combination of a platen, paper feed rollers 120 shiftable away from the platen, a paper deflector shiftable from an ineffective to an effective position where it will aid in introducing a work sheet rearwardly around and beneath the platen, stops for arresting the bottom edge of a work sheet introduced rearwardly around the platen from the front thereof, said stops being shiftable from an effective to an ineffective position, means by 125 which such movements of said deflector and 130

stops are simultaneously effected during the said shifting of said feed rollers, and means operable at will independently of the shifting movement of said feed rollers for effecting such movements of said deflector and stops.

11. In a typewriting or like machine, the combination of a platen, paper feed rollers shiftable away from the platen, a paper deflector shiftable from an ineffective to an effective position where it will aid in introducing a work sheet rearwardly around and beneath the platen, stops for arresting the bottom edge of a work sheet introduced rearwardly around the platen from the front thereof, said stops being shiftable from an effective to an ineffective position, means by which such movements of said deflector and stops are simultaneously effected during the said shifting of said feed rollers, means operable at will independently of the shifting movement of said feed rollers for effecting such movements of said deflector and stops, and means operable at will for effecting a movement of said stops to ineffective position independently of said simultaneous shifting movements of the feed rollers and deflector.

12. In a typewriting or like machine, the combination of a platen, two sets of feed rollers disposed at different points along the platen, the feed rollers of each set being shiftable towards and away from the platen independently of the feed rollers of the other set, stops for arresting the bottom edge of a work sheet introduced rearwardly around the platen from the front thereof, automatically operating means controlled by the movement of one set only of said feed rollers away from the platen for positioning said stops in ineffective position, and means operable at will independently of said automatically operating means for shifting said stops to ineffective position.

13. In a typewriting or like machine, the combination of a platen, two sets of feed rollers disposed at different points along the platen, the feed rollers of each set being shiftable towards and away from the platen independently of the feed rollers of the other set, a paper deflector carried by the carriage in front of the platen to aid in introducing work sheets from the front of the platen rearwardly around and beneath the platen, said deflector being shiftable from an ineffective to an effective position in which it is in the path of the types, stops for arresting the bottom edge of a work sheet introduced rearwardly around the platen from the front thereof, automatically operating means controlled by the movement of one set only of said feed rollers away from the platen for shifting said stops to ineffective position and for shifting the deflector to effective position, and means operable at will

independently of said automatically operating means for shifting said stops to ineffective position.

14. In a typewriting or like machine, the combination of a platen, paper feed rollers shiftable towards and away from the platen, a paper deflector shiftable from an ineffective to an effective position where it will aid in introducing a work sheet rearwardly around and beneath the platen from the front thereof, a line gage shiftable into and out of effective position, stops for arresting the bottom edge of a work sheet introduced rearwardly around the platen from the front thereof, automatically operating means which by a movement of said feed rollers away from the platen causes the line gage to be shifted to ineffective position, causes the paper deflector to be shifted to effective position and causes the stops to be shifted to ineffective position, and means operable at will independently of said automatically operating means for shifting said stops to ineffective position.

15. In a typewriting or like machine, the combination of a platen, paper feed rollers shiftable towards and away from the platen, a paper deflector shiftable from an ineffective to an effective position where it will aid in introducing a work sheet rearwardly around and beneath the platen from the front thereof, a line gage shiftable into and out of effective position, stops for arresting the bottom edge of a work sheet introduced rearwardly around the platen from the front thereof, automatically operating means which by a movement of said feed rollers away from the platen causes the line gage to be shifted to ineffective position, causes the paper deflector to be shifted to effective position and causes the stops to be shifted to ineffective position, means operable at will independently of said movement of the feed rollers for effecting such movements of the line gage paper deflector and stops, and means for shifting said stops to ineffective position independently of the shifting movements of said feed rollers, line gage and deflector.

16. In a typewriting or like machine, the combination of a platen, paper feed rollers shiftable away from the platen, stops for arresting the bottom edge of a work sheet introduced rearwardly around and beneath the platen from the front thereof, said stops being shiftable into and out of effective position and normally occupying an effective position, means for automatically shifting said stops to ineffective position when said feed rollers are shifted away from the platen, and means operated independently of the shifting movement of said feed rollers for shifting said stops from effective to ineffective position.

17. In a typewriting or like machine, the

combination of a carriage, a platen carried thereby, two curved paper deflectors arranged one above the other and extending beneath the platen, means for maintaining 5 said deflectors spaced apart so that they with the platen will form two separated channels through which work sheets may pass, one of said channels being between the platen and the upper deflector, the other channel being 10 between the two deflectors, a third paper deflector carried by the carriage in front of the platen and shiftable from an ineffective position out of the path of the types to an effective position in the paths thereof and 15 where it will direct a work sheet introduced rearwardly past the printing line to the channel between said curved deflectors, and stops shiftable into and out of the channel formed between the two curved deflectors and which 20 stops when in effective position coact with the bottom edge of a work sheet introduced rearwardly through said last mentioned channel.

18. In a typewriting or like machine, the 25 combination of a ribbon guide, a paper deflector shiftable from an ineffective to an effective position, the ribbon guide normally being in the path of the deflector in the movement of the latter to effective position, 30 and means for moving and holding said ribbon guide out of the path of said deflector so that the ribbon guide will not interfere with the movement of the deflector to effective position.

19. In a typewriting or like machine, the 35 combination of a ribbon guide, a paper deflector shiftable from an ineffective to an effective position, the ribbon guide normally being in the path of the deflector in the 40 movement of the latter to effective position, means for moving said deflector to effective position and for at the same time automatically moving the ribbon guide out of the path of the deflector.

20. In a typewriting or like machine, the 45 combination of a paper deflector normally in ineffective position but movable to effective position, a ribbon vibrator normally actuated at each printing operation and 50 which in its normal position extends in the path of movement of the deflector to effective position, means for moving the deflector to effective position and for simultaneously moving the ribbon vibrator from normal position to a position where it will not 55 interfere with the movement of the deflector to effective position.

21. In a typewriting or like machine, the 60 combination of a carriage, a platen carried thereby, a paper deflector carried by the carriage and shiftable from an ineffective to an effective position where it will direct a work sheet introduced into the machine 65 rearwardly past the printing line, a ribbon vibrator carried by the frame of the ma-

chine and in its normal position extending in the path of said deflector in the movement of the latter to effective position, means for shifting said deflector to effective position, and means for automatically shifting the 70 ribbon vibrator out of the path of the deflector.

22. In a typewriting or like machine, the 75 combination of a carriage, a platen carried thereby, a paper deflector carried by the carriage and shiftable from an ineffective to an effective position where it will direct a work sheet introduced into the machine 80 rearwardly past the printing line, a ribbon vibrator carried by the frame of the machine and in its normal position extending in the path of said deflector in the movement of the latter to effective position, means for shifting said deflector to effective position, and means for automatically shifting the 85 ribbon vibrator out of the path of the deflector, said last mentioned means comprising a bar that extends longitudinally substantially throughout the length of the carriage and is operatively connected to move 90 in unison with said deflector, and a movable support for said vibrator which is moved by said bar.

23. In a typewriting or like machine, the 95 combination of a carriage, a platen carried thereby, paper feed rollers shiftable to and away from the platen, a line indicator shiftable to and from effective position, a paper deflector shiftable to and from effective position, a ribbon vibrator shiftable from its 100 normal position, and automatically operating means for shifting said line indicator from effective position, for shifting said deflector to effective position, and for shifting said vibrator from normal position when 105 said feed rollers are shifted away from the platen.

24. In a typewriting or like machine, the 110 combination of a carriage, a platen carried thereby, paper feed rollers shiftable to and away from the platen, a line indicator shiftable to and from effective position, a paper deflector shiftable to and from effective position, a ribbon vibrator shiftable from its 115 normal position, end stops for arresting the paper, which are shiftable to and from effective position, and automatically operating means for shifting said line indicator from effective position, for shifting said deflector to effective position, for shifting said vibrator from normal position and for shifting said end stops from effective position when 120 said feed rollers are moved away from the platen.

25. In a typewriting or like machine, the 125 combination of a carriage, a platen carried thereby, paper feed rollers shiftable to and away from effective position, a paper deflector shiftable to and away from effective position, a ribbon vibrator shiftable from 130

normal position, and automatically operating means for shifting said vibrator from normal position and for shifting said deflector to effective position when said feed rollers are shifted away from effective position.

26. In a typewriting or like machine, the combination of a carriage, a platen carried thereby, paper feed rollers shiftable to and away from the platen, a line indicator shiftable to and from effective position, a paper deflector shiftable to and from effective position, a ribbon vibrator shiftable from its normal position, automatically operating means for shifting said line indicator from effective position, for shifting said deflector to effective position, and for shifting said vibrator from normal position when said feed rollers are shifted away from the platen, and additional paper feed rollers coacting with the platen and which are unaffected by said first mentioned feed rollers and the said parts which are automatically moved in conjunction therewith.

27. In a typewriting or like machine, the combination of a carriage, a platen carried thereby, paper feed rollers shiftable to and away from the platen, a line indicator shiftable to and from effective position, a paper deflector shiftable to and from effective position, a ribbon vibrator shiftable from its normal position, end stops for arresting the paper, said stops being shiftable to and from effective position, automatically operating means for shifting said line indicator from effective position, for shifting said deflector to effective position, for shifting said vibrator from normal position and for shifting said end stops from effective position when said feed rollers are moved away from the platen, and additional paper feed rollers coacting with the platen and which are unaffected by said first mentioned feed rollers and the said parts which are automatically moved in conjunction therewith.

28. In a typewriting or like machine, the combination of a platen, a paper deflector shiftable from an ineffective to an effective position in the path of the types where it will aid in directing a work sheet introduced rearwardly from the front of the platen across the printing line and beneath the platen, two additional paper deflectors arranged one above the other beneath the platen and providing a channel between them to which the first mentioned paper deflector when in use guides a work sheet, a ribbon vibrator shiftable from normal position to an ineffective position, a finger piece, and means controlled by a single operation thereof for shifting said ribbon vibrator from normal position and for shifting said shiftable deflector to effective position.

29. In a typewriting or like machine, the

combination of a platen, a paper deflector shiftable from an ineffective to an effective position in the path of the types where it will aid in directing a work sheet introduced rearwardly from the front of the platen across the printing line and beneath the platen, two additional paper deflectors arranged one above the other beneath the platen and providing a channel between them to which the first mentioned paper deflector when in use guides a work sheet, a ribbon vibrator, shiftable from normal position to an ineffective position, paper feed rollers shiftable from effective position, a finger piece, and means controlled thereby for shifting said feed rollers out of effective position for shifting said ribbon vibrator from normal position, and for shifting said shiftable deflector to effective position.

30. In a typewriting or like machine, the combination of a platen, a paper deflector shiftable from an ineffective to an effective position in the path of the types where it will aid in directing a work sheet introduced rearwardly from the front of the platen across the printing line and beneath the platen, two additional paper deflectors arranged one above the other beneath the platen and providing a channel between them to which the first mentioned paper deflector when in use guides a work sheet, a printing line indicator shiftable from normal effective position to an ineffective position, a ribbon vibrator shiftable from normal position to an ineffective position, a finger piece, and means controlled thereby for shifting said line indicator and ribbon vibrator from their normal positions to abnormal or ineffective positions and for shifting said shiftable deflector to effective position.

31. In a typewriting or like machine, the combination of a platen, a paper deflector shiftable from an ineffective to an effective position in the path of the types where it will aid in directing a work sheet introduced rearwardly from the front of the platen across the printing line and beneath the platen, two additional paper deflectors arranged one above the other beneath the platen and providing a channel between them to which the first mentioned paper deflector when in use guides a work sheet, a ribbon vibrator shiftable from normal to an ineffective position, paper feed rollers shiftable from effective to ineffective positions, a printing line indicator shiftable from normal or effective to ineffective positions, a finger piece, and means controlled thereby for shifting said feed rollers, ribbon vibrator and line indicator from normal to abnormal or ineffective positions and for shifting said shiftable deflector to effective position.

32. In a typewriting or like machine, the

- combination of a carriage, a platen carried thereby, means for aiding in directing a work sheet rearwardly beneath the platen from in front thereof including a paper deflector carried by the carriage and movable from an ineffective position out of the paths of the types to an effective position in the paths thereof, paper end stops shiftable into and out of effective position and normally occupying an effective position; means for controlling said deflector and end stops by a single operation for moving said stops from effective position when the deflector is moved to effective position, and means by which the end stops may be separately controlled. 33. In a typewriting or like machine, the combination of a carriage, a platen carried thereby, means for aiding in directing a work sheet rearwardly beneath the platen from in front thereof including a paper deflector carried by the carriage and movable from an ineffective position out of the paths of the types to an effective position in the paths thereof, paper end stops shiftable into and out of effective position; a printing-line indicator shiftable to and from effective position, paper feed rollers shiftable to and from effective position, means that enable said feed rollers, deflector, line indicator and end stops to be shifted at a single operation, and means which enable said deflector, indicator and end stops to be shifted independently of said feed rollers. 34. In a typewriting or like machine, the combination of a carriage, a platen carried thereby, means for aiding in directing a work sheet rearwardly beneath the platen from in front thereof including a paper deflector carried by the carriage and movable from an ineffective position out of the paths of the types to an effective position in the paths thereof, paper end stops shiftable into and out of effective position; a printing-line indicator shiftable to and from effective position; paper feed rollers shiftable to and from effective position, means that enable said feed rollers, deflector, line indicator and end stops to be shifted at a single operation; means which enable said deflector, indicator and end stops to be shifted independently of said feed rollers, and means which enable said end stops to be shifted independently of said rollers, line indicator and deflector. 35. In a typewriting or like magazine, the combination of a carriage, a platen carried thereby, a paper deflector carried by the carriage and shiftable from an ineffective to an effective position, a printing-line indicator shiftable to and from effective position; intermediate actuating connections between said deflector and indicator for causing the indicator to be shifted to ineffective position when the deflector is shifted to effective position, paper end stops shiftable into and out of effective position, an actuating member connected with said stops and extending in the path of movement of certain of said intermediate actuating connections for shifting the stops in unison with said deflector and indicator, and a finger piece connected to said actuating member for shifting the stops independently of said deflector and indicator. 36. In a typewriting or like machine the combination of a carriage, a platen carried thereby, a paper deflector carried by the carriage and shiftable from an ineffective to an effective position, a printing-line indicator shiftable to and from effective position; intermediate actuating connections between said deflector and indicator for causing the indicator to be shifted to ineffective position when the deflector is shifted to effective position, paper end stops shiftable into and out of effective position, an actuating member connected with said stops and extending in the path of movement of certain of said intermediate actuating connections for shifting the stops in unison with said deflector and indicator, a finger piece connected to said actuating member for shifting the stops independently of said deflector and indicator, a paper feed roller shiftable to and from effective position, a shiftable carrier on which said feed roller is mounted, an abutment on certain of said intermediate actuating connections which is in the path of movement of and is adapted to be engaged by said carrier when the latter is shifted away from the platen and thereby cause the paper feed roller, indicator, deflector and stops to be shifted in unison, and a finger piece connected to said intermediate actuating connections and by which the indicator, deflector and stops may be shifted independently of said feed roller. 37. In a typewriting machine, the combination of a carriage, a cylindrical platen carried thereby, a paper deflector mounted on the carriage in front of the platen for shifting movement from a normally ineffective position to an effective position where it will aid in directing a work sheet rearwardly and downwardly past the printing line, from the front of the platen, actuating means for thus moving said deflector limited extents in both directions, and means that enable said deflector to be disconnected from its actuating means and moved beyond its normal limit of motion in one direction in order to give access to parts beneath it. 38. In a typewriting machine, the combination of a carriage, a cylindrical platen carried thereby, a paper deflector mounted on the carriage in front of the platen for shifting movement from a normally ineffective position to an effective position where it will aid in directing a work sheet rearwardly and downwardly past the printing

line from the front of the platen, and means which enable said deflector at will to be moved beyond said normal position in order to give ready access to parts which are difficult to gain access to when the deflector is in its normal position.

39. In a typewriting machine, the combination of a carriage, a cylindrical platen carried thereby, a ribbon vibrator, a paper deflector mounted on the carriage in front of the platen for shifting movement from a normally substantially horizontally disposed ineffective position to a downwardly and rearwardly inclined effective position where it will aid in directing a work sheet rearwardly and downwardly past the printing line from the front of the platen, and means which enable said deflector at will to be moved forward beyond said normal position to a substantially vertically disposed position in order to give ready access to the ribbon vibrator which is difficult to gain access to when the deflector is in its normal position.

40. In a typewriting machine, the combination of a carriage, a cylindrical platen carried thereby, a ribbon vibrator, a paper deflector mounted on the carriage in front of the platen for shifting movement from a normally substantially horizontally disposed ineffective position to a downwardly and rearwardly inclined effective position where it will aid in directing a work sheet rearwardly and downwardly past the printing line from the front of the platen, actuating means for thus moving said deflector limited extents in both directions, and means that enable said deflector to be disconnected from its actuating means and moved forward to a substantially vertically disposed unobstructing position beyond its limit of motion to normal position in order to give access to parts beneath it.

41. In a typewriting or like machine, the combination of a ribbon guide, a paper deflector shiftable into and out of effective position, means for moving said ribbon guide out of the path of said deflector in order to enable the latter to be shifted to effective position, and means which enable said deflector to be shifted beyond its normal extent of movement from effective to ineffective position in order to give more ready access to said ribbon vibrator.

42. In a typewriting or like machine, the combination of a ribbon guide, a paper deflector shiftable into and out of effective position, automatically operating means for shifting said ribbon guide out of its normal position when said deflector is shifted to effective position, and means for disconnecting said deflector from said operating means to enable the deflector to be shifted to a position beyond its said shifting movement and give better access to said vibrator.

43. In a typewriting or like machine, the combination of a platen, feed rollers cooperative therewith above the printing line and movable towards and from the platen, a paper deflector arranged in front of the platen and shiftable from an ineffective position out of the path of the types to an effective position in the path thereof where said deflector is effective to guide a work sheet introduced rearwardly past the printing line, automatically operating means for shifting said deflector to effective position when said feed rollers are moved away from the platen, and means for disconnecting said deflector from its operating means in order to enable the deflector to be moved to a further position where it will give better access to parts that are rendered difficult of access to by reason of the position of the deflector when connected to its actuating means.

44. In a typewriting or like machine, the combination of a platen, two sets of feed rollers disposed at different points along the platen, the feed rollers of each set being shiftable towards and away from the platen independently of the feed rollers of the other set, a paper deflector carried by the carriage in front of the platen to aid in introducing work sheets from the front of the platen rearwardly around and beneath the platen, said deflector being shiftable from an ineffective to an effective position in which it is in the path of the types, automatically operating means for shifting said deflector to effective position when one set of said feed rollers is moved away from the platen, means which enable said deflector to be shifted at will into effective position independently of the operation of said automatically operating means, and means for disconnecting said deflector from its operating means in order to enable the deflector to be moved to a further position where it will give better access to parts that are rendered difficult of access to by reason of the position of the deflector when connected to its actuating means.

45. In a typewriting machine, the combination of a carriage, a cylindrical platen carried thereby, a paper deflector pivoted on the carriage for shifting movement from a normally ineffective position to an effective position where it will aid in directing a work sheet rearwardly and downwardly past the printing line from the front of the platen, actuating means for thus moving said deflector, and means that enable said deflector to receive a slight axial movement and by such movement to disconnect the deflector from its actuating means and thus enable the deflector to be shifted around its axis to a further position where it affords unobstructed access to parts in front of the platen that otherwise are difficult to gain access to.

46. In a typewriting machine, the combi-

- nation of a carriage; a cylindrical platen carried thereby, a paper deflector pivoted on the carriage for shifting movement from a normally ineffective position to an effective position where it will aid in directing a work sheet rearwardly and downwardly past the printing line from the front of the platen, actuating means for thus moving said deflector, said actuating means including an actuating arm, a detachable connection between said arm and the deflector that is detached or broken by an axial movement of said deflector, and means which enable said deflector to receive an axial movement to break said connection in order that the deflector may receive a further pivotal movement to a position where it will give better access to parts in front of the platen.
47. In a typewriting machine, the combination of a carriage; a cylindrical platen carried thereby; a paper deflector carried by the carriage and comprising a portion bent on itself to provide an enclosed longitudinally extending channel; and means for mounting said deflector on the carriage for movement into and out of effective position, said means comprising movable supporting arms having laterally extending ears or lugs that are received in said channel at the ends thereof and are secured in place therein.
48. In a typewriting machine, the combination of a carriage; a cylindrical platen carried thereby; a paper deflector carried by the carriage and comprising a sheet metal strip bent thereunder along one longitudinally extending edge portion of the deflector to provide a longitudinally extending enclosed channel on the side of the deflector opposite its contact face; and means for pivotally supporting said deflector for movement on the carriage into and out of effective position, said means comprising sheet metal pivoted supporting arms each bent inwardly at its free end where it is received in said channel at an end thereof where it is secured to said deflector.
49. In a typewriting machine, the combination of a platen, a plurality of widely separated aligned paper feed rollers which coact with the platen above the printing line, carrying means on which said feed rollers are mounted for movement towards and away from the platen, and a side edge paper gage carried by and movable with said carrying means.
50. In a typewriting machine, the combination of a platen, a plurality of widely separated aligned paper feed rollers which coact with the platen above the printing line, carrying means on which said feed rollers are mounted for movement towards and away from the platen, a side edge paper gage carried by and movable with said carrying means, and means for affording an adjustment of said gage longitudinally of the platen on said carrying means.
51. In a typewriting machine, the combination of a platen, pivoted arms that extend over the platen, a spindle extending between and carried by said arms, widely separated paper feed rollers on said spindle and which coact with the platen above the printing line, and a side edge paper gage carried by said spindle and extending rearward therefrom to coact with work sheets that pass beneath said feed rollers.
52. In a typewriting machine, the combination of a platen, pivoted arms that extend forward over the platen from the rear thereof, a spindle extending between and carried by said arms, widely separated paper feed rollers on said spindle and which coact with the platen above the printing line, a side edge paper gage carried by said spindle and extending rearward therefrom to coact with work sheets introduced from the rear of the platen and which pass beneath said feed rollers, and means for affording an adjustment of said gage along said spindle and for securing the gage in the different set positions to which it may be adjusted.
53. In a typewriting machine, the combination of a platen, two sets of widely separated paper feed rollers which coact with the platen in front thereof and above the printing line, one set of said widely separated feed rollers being shiftable towards and from the platen independently of the feed rollers of the other set, individual operatively connected carriers for the set of independently shiftable feed rollers, and a side edge paper gage carried by one of said carriers and cooperative with a work sheet introduced from in front of and inserted beneath the platen.
54. The combination of a platen, feed rollers shiftable into and out of contact with the platen, end stops, and means for automatically moving the end stops to effective position when the feed rollers are moved into contact with the platen and for moving said end stops to ineffective position when said feed rollers are moved out of contact with the platen.
55. The combination of a platen, feed rollers shiftable into and out of contact with the platen, end stops, means for automatically moving the end stops to effective position when the feed rollers are moved into contact with the platen and for moving said end stops to ineffective position when said feed rollers are moved out of contact with the platen, and means that enable said end stops to be shifted to ineffective position independently of the shifting movement of said feed rollers.
56. The combination of a platen, feed rollers disposed at different points along the

- platen and including a pair of outer margin feed rollers that may be moved together into contact with the platen independently of the intermediate feed roller or rollers, stops for arresting the bottom edge of a work sheet introduced rearwardly around and beneath the platen from the front thereof, and means for automatically moving said end stops to effective position when said outer margin feed rollers are moved into contact with the platen and for rendering said end stops ineffective when said outer margin feed rollers are moved away from the platen. 5
57. The combination of a platen, feed rollers including a pair of margin feed rollers shiftable towards and away from the platen, a paper deflector carried by the carriage in front of the platen to aid in introducing work sheets from the front of the platen rearwardly around and beneath the platen, said deflector being shiftable from an ineffective to an effective position, and automatically operating means for shifting said stops to ineffective position and the deflector to effective position where said pair of margin feed rollers is moved away from the platen. 20
58. The combination of a platen, end stops located at different distances from the point of introduction of the paper into the machine, paper feed rollers including a pair of margin feed rollers movable into and out of contact with the platen, and automatically operating means for moving the end stop or stops nearest the point of introduction of
- paper into the machine to ineffective position when said pair of margin feed rollers is moved out of contact with the platen so that a paper with which said margin feed rollers coact may be moved past said last mentioned end stop or stops and be arrested by the other end stop or stops located more remote from the point where the work sheets are introduced into the machine. 40
59. In a typewriting or like machine the combination of a carriage, a platen carried thereby, paper feed rollers shiftable to and away from the platen, a line indicator shiftable to and from effective position, a paper deflector shiftable to and from effective position, a ribbon vibrator shiftable from its normal position, automatically operating means for shifting said line indicator from effective position, for shifting said deflector to effective position, and for shifting said vibrator from normal position when said feed rollers are shifted away from the platen, and one or more additional feed rollers coacting with the platen and which are unaffected by the shifting of the first mentioned feed rollers into contact with the platen and the concurrent automatic operation of the parts controlled thereby. 45
